(57) **CLAIM**

I claim, the ornamental design for an umbilical cord cutter and clamper, as shown and described herein.

DESCRIPTION

FIG. 1 is a rear top left perspective view of the umbilical cord cutter and clamper, showing my new design;

FIG. 2 is a front bottom left perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a left side elevation view thereof;

FIG. 8 is a right side elevation view thereof; and,

FIG. 9 is an exploded rear top left perspective view thereof. The surface shading vertical and horizontal lines on the claimed portion illustrated in FIGS. 1-9 are provided only to indicate the character and/or any contour or curvature of the surfaces. They do not indicate color, texture, markings that actually exist thereon, indicia, graphic representations, surface treatment, or any other ornamentation applied to the umbilical cord cutter and clamper.
